UNITED STATES PATENT OFFICE.

ETIENNE WITZBERGER, OF CARNEGIE, PENNSYLVANIA, ASSIGNOR TO WITZBERGER
HEATING APPLIANCES COMPANY, A CORPORATION OF PENNSYLVANIA.

DESIGN FOR A HEATER.

•60,390.

Specification for Design.

Patented Feb. 7, 1922.

Application filed May 27, 1921. Serial No. 473,158. Term of patent 7 years.

To all whom it may concern:

Be it known that I, ETIENNE WITZBERGER, a citizen of the United States, residing at Carnegie, in the county of Allegheny and State of Pennsylvania, have invented a new, original, and ornamental Design for a Heater, of which the following is a specification, reference being had to the accompanying drawing, forming part thereof.

The figure is a front elevation of a heater showing my new design.

I claim:

The ornamental design for a heater, as shown.

ETIENNE WITZBERGER.
